UNITED STATES PATENT OFFICE

GEORGE J. DUNBAUGH, JR., OF CHICAGO, ILLINOIS, ASSIGNOR TO CHAMPION MANUFACTURING COMPANY, OF CHICAGO, ILLINOIS, A CORPORATION OF ILLINOIS

TANK INDICATOR

Application filed October 10, 1928. Serial No. 687,673.

My invention relates to indicators for determining the level of gasoline or other liquid in tanks, and has among its objects the production of a device of the kind described, which is simple, convenient, compact, durable, reliable, efficient and satisfactory for use wherever found applicable. 55

Many other objects and advantages of the construction herein shown and described will be obvious to those skilled in the art from the disclosures herein given. 60

To this end my invention consists in the novel construction, arrangement and combination of parts herein shown and described, 15 and more particularly pointed out in the claim.

In the drawings, wherein like reference characters indicate like or corresponding parts,

20 Fig. 1 shows my device as applied to a motor vehicle;

Fig. 2 is a sectional view of the gasoline tank with my device applied thereto;

Fig. 3 is a section taken substantially on line 3—3 of Fig. 2;

Fig. 4 is a plan view of the indicator portion of my device, taken from the front thereof;

Fig. 5 is a section taken substantially on line 5—5 of Fig. 4; and

30 Fig. 6 is a section taken substantially on line 6—6 of Fig. 5.

In the drawings, wherein I have illustrated the preferred embodiment of my invention, there is shown a motor vehicle of any desired 35 construction or type and having the usual tank or receptacle 1 for holding a supply of gasoline. The tank has a filling inlet 2 and is provided with an outlet opening 3. A flanged fitting 4 is positioned about the opening 3 of the tank, the outer end of said fitting being preferably threaded.

A bracket is adapted to be inserted through the fitting and to extend within the tank in order to carry a float mechanism for actuating 45 an indicator located at a remote point. This bracket is formed of any desired material, aluminum being found especially desirable and suitable for the purpose, the same comprising an arm 5, at the ends of which are arranged arms 6 and 7, respectively, these arms

being formed integrally with and lateral to the arm 5. Aligned apertures are provided through the portions 6 and 7 and into these apertures are inserted bushings, or bearings 8 and 9, respectively, of bakelite, or any other suitable material.

Integral with the bracket and arranged transversely thereto at the outer end is a closure disk 10, adapted to seat on the fitting 4 so as to prevent the passage of liquid therethrough. A collar 11 is arranged to be screwed onto the fitting 4 over the closure disk so as to clamp the closure disk in place against movement.

A bored sleeve portion 12 extends from the closure disk 10, in line with the bored portion 7, but on the opposite side of said disk, the outer end of said board portion 12 being threaded so as to receive a clamping nut 13, as will be hereinafter described. 70

A float mechanism comprising a float 14 arranged at one end of a bent rod having legs 15 and 16 is adapted to be arranged within the tank and carried by the bracket, the float rising or falling with changes in the level 75 of the gasoline. In Fig. 2 the float is shown at its lowest position, or, in other words, the tank 1 is empty. The leg 16 of the float mechanism is inserted through the aligned bearings 8 and 9 thus insuring positive action without binding in response to a change in the level of the liquid, the free end of the leg 16 having a pin 17 projecting radially thereof. A nut or collar 8' is secured to the leg 16 to bear against the bushing 8 and prevent longitudinal movement of the float mechanism inwardly beyond the bracket. 80

A flexible shaft 18 has one end connected to an extension 19 rotatably arranged within the bore of the closure disk 10, the free end 90 of the extension 19 having a socket to receive the free end of the rod portion 16 and having a slot 20 inwardly of the outer end of the socket, to slidably receive the pin 17. Any rotational movement of the rod 16 will be 95 transmitted to the flexible shaft through the pin and slot connection.

A conduit or sheath 21, having an enlarged portion 22 is arranged about the flexible shaft 18 and is retained against longitudinal move- 100

ment by having its enlarged portion 22 clamped between the sleeve 12 and the nut 13. In order to transmit the rotational movement of the flexible shaft to a suitable indicating means, so that the amount of gasoline in the tank may be ascertained, I have arranged an indicator at the instrument board of the vehicle with a flexible shaft and casing run to the instrument board as shown in Fig. 1.

10 In Fig. 5, a cup-shaped member 26, having a flange 27 is inserted through an opening in the instrument board 25 and a dial portion 28 is arranged across the interior of the cup. A bezel 29 is inserted into the cup to bear against the dial and hold it in place, there being spacer rings 31 and 32 to further assist in this purpose. A glass or transparency 30 is held in place in the bezel and through which the dial may be viewed. A bearing part 34 is arranged within the cup 26 and is provided with a threaded extension to project beyond the cup, this extension adapted to cooperate with the nut 13 for securing the end of the conduit 21 in place therat.

25 The part 34 is provided with a pair of parallel laterally spaced bores 35 and 36 therethrough, the former intended for receiving the flexible shaft 18 and the latter to form a bearing for a spindle shaft 37 upon which a 30 needle or pointer 38 is mounted so as to move across the face of the dial 28. A plate 33 is arranged across the cup intermediate the spacer rings 31 and 32 to form a second bearing for the spindle 37. The outer portion of the bore 36 is enlarged so as to frictionally receive a plug 39 extending through the cup and by means of which the spindle may be adjusted from the exterior of the cup.

40 A shaft extension part 23 is attached at one end by suitable means to the end of the flexible shaft 18 arranged within the bearing 35, said extension having a pair of axially spaced rounded enlargements 24 thereon to bear against the wall of the bearing aperture 35 and provide an annular chamber therebetween. Lock nuts 34' may be arranged on the part 34 to clamp it in place within the cup, and a bracket part 42 may be arranged to be secured to the cup by bolts 43, the ends of 45 said bracket bearing against the inside wall of the instrument board 25.

50 It will be noted that there are no gears at the tank portion of the device and it therefore becomes necessary to provide gears or other motion reducing means at the indicator portion so that the needle will not be revolved through more than a single revolution. This reduction of angular movement of the needle is done by arranging intermeshing 55 gears or pinions 40, 41 on the shafts 37 and 23. Obviously, any movement of the float will be transmitted directly to the flexible shaft through the pin and slot connection, and, in turn, transmitted to the needle 60 through the meshing gears.

Having thus described my invention, it is obvious that various immaterial modifications may be made in the same without departing from the spirit of my invention; hence I do not wish to be understood as limiting myself to the exact form, construction, arrangement and combination of parts herein shown and described, or uses mentioned.

What I claim as new and desire to secure by Letters Patent is:

75 In a device of the kind described and in combination, a tank having an opening therein, a fitting arranged at the opening, a one-piece bracket insertable into the opening from the exterior thereof and having aligned bearings, means for securing the bracket to the fitting, float means arranged in the tank, a bent one-piece rod having one end secured to the float means and having its other end journaled in the bearings, a flexible shaft projecting into the bracket, a member secured to the flexible shaft and having a slotted socket adapted to receive one end of the bent rod, and a pin projecting from the rod and engaging the slot.

80 In testimony whereof, I have hereunto signed my name.

90 GEORGE J. DUNBAUGH, Jr.
